SHOT

Samuel Alfred Tenison, South Pasadena, Calif.

Application July 9, 1934, Serial No. 734,363

22 Claims. (Cl. 272—59)

This invention relates to a shot employed in the athletic field event of putting the shot.

These shot are relatively heavy small spheres employed in eight, ten and twelve pound sizes 5 for high school events and sixteen pound sizes for college events. They are customarily constructed from a sand molded metal shell filled with a weighting material such as lead. The shot of the prior art is constructed, as stated, of 10 a generally spherical shell cast in a sand mold and accordingly securing a perfectly spherical shell is difficult, if not entirely impossible. The shells are cast with one or more suitable openings into which may be poured molten lead to 15 fill the interior and provide the necessary density. When such shot are completed they cannot be adjusted for controlling the total weight except by drilling out a portion of the lead filler which, it is obvious, results in a very unbalanced 20 sphere. It is extremely important that the shot be kept at the proper weight and be accurately balanced, for if the shot is put for a record, it must be weighed before the record can be recognized and, if found to be of less weight than 25 the rules require, the record is not, of course, recognized. In normal use the shell of the shot is gradually worn by abrasion and chipping when it comes into contact with the field and in time 30 reduces its weight materially, but in the case of the shells of the prior art, it is difficult to control the weight, since the interior is normally completely filled and the shot must accordingly be discarded.

This difficulty in reduction of weight of the 35 shot of the prior art and its disadvantages has been recognized and provision for controlling the weight has been made by incompletely filling this generally spherical shell with the weighting material. By this means it has been possible to 40 remove the closure cap and add a small amount of weighting material. Since the shell is not completely filled, but space is left on one side, the original shot as manufactured is definitely unbalanced and the addition of further loose 45 weighting material does not improve the balance of it.

The act of putting the relatively heavy sphere 50 requires a rather high degree of skill in properly holding the shot in the hand and propelling it forward by a combination of arm and body exertion. The shot, after leaving the hand, describes a trajectory which is, to some extent, controlled by the balance of the sphere. In the shot now employed and known to the prior art, 55 no provision was made for balancing or con-

trolling the balance of the shot and, as a result, many were decidedly unbalanced, resulting in marked deviation from a normal or proper trajectory.

It is accordingly among the objects of this invention to provide a perfectly spherical shot. A further object includes the provision of a shot which may be readily controlled as to total weight.

An additional object includes the provision of a shot which may be readily and accurately controlled as to balance.

An important object is the provision of a shot with a die cast shell whereby a perfect sphere may be obtained which may also be provided with a slightly roughened surface.

Another object is to provide a unitary steel die cast shell with integral receptacles or cylinders for the reception of weighting and balancing material.

These objects individually and in combination, as well as other objects which will be apparent from the sequent description, are all embraced within this invention, the preferred embodiment of which is illustrated in the accompanying drawings, wherein:

Figure 1 is a view chiefly in cross section of a complete shot;

Figure 2 is a view in cross section, taken along the lines II—II of the cylinder of Fig. 1;

Figure 3 is a cross section view of the inner shell and cylinders showing the shot in an early stage of manufacture;

Figure 4 is a cross section looking in the direction of the arrows of the section line IV—IV of Fig. 3;

Figures 5, 6 and 7 are plan, side and section views of the closure cap, respectively;

Figure 8 is a view of the die employed in casting the inner hemispherical shells shown as joined in Fig. 3;

Figure 9 is a cross section view of the die used for casting the outer shell on the inner joined hemispheres; and

Figure 10 is a cross section along the line X—X of Fig. 9, looking in the direction of the arrows.

The embodiment of the invention as illustrated in Fig. 1 comprises an inner shell 2 composed of two hemispheres 4 and 6, preferably prepared in the manner hereinafter described in connection with Fig. 8. These two hemispheres are suitably joined at the point 8 and may form a completed shell, but usually an outer shell, hereinafter described, is used with the inner shell. Each hemisphere is preferably integrally cast with

cylinders 10 and 12, respectively, said cylinders 10 and 12 being generally identical except that adjacent one of the cylinders, as for example 12, are provided openings 14 and 16.

5 The cylinders 10 and 12 are, as stated above, preferably cast integral with the hemispheres of the inner shell, but, as will be apparent, they may be otherwise cast in connection with the shell or may be suitably inserted in this or other types 10 of shell, as may be desired. By attaching such cylinders, or similar concave, reentrant receptacles to ordinary shells, it is possible to secure some of the advantages of one feature of the present invention.

15 Surrounding the inner shell formed from the two hemispheres 4 and 6 may be an outer substantially continuous sphere 20. This outer sphere may be provided with a slightly roughened surface 21 formed in the manner hereinafter described. The outer shell 20 is also provided with suitable openings 22 for the reception of closure caps 24, which are so formed as to present a continuous surface with that of the sphere when they are in place. The caps may be attached to the outer shell by screw threads 26 or other fastening means. In order to screw the caps 24 into place, suitable means, such for example as spanner wrench openings 28, may be provided in the outer surface of the caps.

25 30 The receptacles, or, more specifically, cylinders 10 and 12, are designed for the reception of weighting and balancing material, and for this purpose are preferably provided with a plurality of holes 30 to receive individual weighting and balancing units. As illustrated, there are four such holes uniformly placed in each cylinder. It will be obvious that instead of four uniformly positioned holes, a larger number, as for example five, in which one hole is directly in the 35 center of the cylinder and may be of larger or smaller size than the others, may be provided. The central holes, under such conditions, are used primarily when it is intended only to increase the total weight of the shot without affecting its 40 balance. This is accomplished by adding an equal amount of secondary weighting material to the central hole on each side. The holes 30 provided in the cylinders 10 and 12 are adapted to receive weighting and balancing members such 45 as discs, or balls 32. These balls are introduced through the openings in the outer shell and are held in their proper position at the bottom of the holes by compression springs 34 placed under slight compression when the closure caps 24 are 50 55 screwed into place.

The interior of the shell is filled with a primary weighting material 36 which may be introduced as a molten liquid through the slot opening 16. Molten primary weighting material is 60 poured through the slot opening 16, the air escaping through the air hole 14, until it completely fills the center of the sphere and also the slot opening 16 and the air hole 14, as shown in Fig. 1. By placing these openings at the 65 positions indicated, the shell can be completely filled with molten material which results in a substantially, although possibly not completely, balanced unit. Obviously, these openings might be substituted by openings placed elsewhere as, 70 for example, at the bottom of an opening in the cylinder such as 30, or, if desired, another opening might be provided in the shell itself, but these are not as desirable as the preferred openings 14 and 16.

75 The method of preparing the die cast outer

shell and the means whereby this method may be carried out is illustrated more particularly in Figs. 8 and 9, the former showing in cross section the apparatus for preparing the inner shell composed of the two hemispheres with their attendant integrally cast cylinders. This apparatus comprises a stationary die block 50 with concavities 52 of the dimensions corresponding to those of the hemispheres 4 and 6. Near the circumferential edge of one cavity 52 is provided a shoulder 54 which leaves an outer annular groove around this portion to join with the other hemisphere which is provided with a corresponding inner annular groove by the shoulder 56. The hemispherical cavities 52 are substantially filled with cores 58 and 59 which define spaces 60 within which the inner hemispheres are cast. In the cores 58 and 59 are cylindrical openings 62 in which are formed the cylinders 10 and 12. A suitable opening in the stationary die block 50 permits the entry of the movable cores 64 and 65 provided with circular extensions 66 that correspond to the openings 30 in the cylinders 10 or 12.

10 The core 59 is substantially identical with core 58 except that, as stated above, it is provided with a shoulder 55 corresponding to the shoulder 54 on the die block. The movable core 65 is otherwise substantially identical with 64 and is provided with extensions 15 and 17 to make the air hole and weighting material introduction slot, 20 respectively. Cores 58 and 59 are held in proper position by a movable die block 68.

15 The apparatus assembled as shown in Fig. 8, molten metal or alloys amenable to steel die casting operations, as for example, "Zamak" 35 metal, an alloy of zinc, copper, aluminum and magnesium, is introduced through the opening 70 where it flows upward under suitable pressure to dividing passageways 72 and 74. These passages 72 and 74 conduct the metal to the spaces 60 and 40 form two hemispheres with integral cylinders.

When the die cast hemispheres have been removed from the dies, they are joined as shown in Fig. 3, by forcing the two hemispheres together at their point of juncture 8 wherein the inner and outer annular grooves coact. There is thus formed a substantially spherical shell from the two hemispheres with their integral cylinders or receptacles.

45 This inner sphere is then cast around with a unitary spherical shell in the manner illustrated in Fig. 9. The inner two piece spherical shell 2 is supported in a steel die block 80 by means of two movable cores 82 and 84. The die block 80 is provided with a spherical cavity 86 corresponding in dimensions to the outer shell 20. The movable core 82 is provided with extensions 88 to partially fill the openings 30 in the cylinder 10 and thereby prevent molten metal from filling the holes. A suitable facing 90 on the core forms a recess for the screw cap 24.

50 The movable core 84 is substantially identical with 82 except that it has additional projections 92 and 94 to fill the air hole and weighting material introduction slot, respectively, that were formed in the inner shell and to continue said hole and slot through a portion of the outer shell. With the various parts arranged as illustrated in Fig. 9, molten metal amenable to die casting as, 65 for example, "Zamak" metal, described above, is introduced through the opening 96 and fills the cavity between the inner shell 2 and the die 86 except where limited by the movable cores 82 and 84. The outer shell being cast as a complete 70 75

sphere provides a uniformly finished spherical shell.

If the sphere is cast in a smooth steel die, the surface will be smooth and it may remain smooth, but it may also be desirable to provide the shot with a slightly roughened surface which can be readily accomplished in preparing the shot according to the teachings of this invention by roughening the exterior surface of the cavity 86 by striking the surface with a small instrument, on the end of which are small projections. These indentations on the die will make protrusions similar to a sand blast on the surface of the shell. The character of this surface is indicated at 21, Figure 1, and is generally similar to that of a sand blast, adding materially to the appearance and giving the shot a more satisfactory "feel" in the hands of the athlete.

The die casting operation as carried out in the apparatus illustrated in Fig. 9 produces a perfectly spherical shell generally similar to that shown in Fig. 1, except for the primary and secondary weighting material, screw caps and spring members. The shell may now be filled with suitable weighting material as, for example, lead, by heating it until it is molten and then introducing it through the slot 16, while air is permitted to flow out through the air hole 14. Sufficient weighting material is introduced to completely fill the interior of the shell and also the slot 16 and air hole 14. Such molten material upon cooling will contract slightly and firmly grip the cylinders 10 and 12, whereby it is absolutely stationary within the shell and will not move around.

Suitable screw threads 26 are then made in the opening provided for the screw caps. If the screw caps are now put in place, the shot will be complete, substantially balanced, but probably lighter than regulations require. To bring the shot up to proper weight, the caps 24 are removed and a suitable number of weighting members as, for example, balls 32 are inserted in equal numbers into each cylinder 10 and 12 and divided among the openings 30 thereof. If the shot is not accurately balanced, a larger number of weighting and balancing members 32 may be inserted into one or more openings 30, as for example 33, to accurately balance the shot. The proper opening 30 into which the additional balancing member or members 33 are to be inserted can be determined by noting the amount and position of the unbalance in the shot.

If, after long use, the shot is reduced in weight additional weighting members may be added, if desired, taking care, of course, to again accurately balance the shot.

The invention has been particularly described with reference to a preferred embodiment, which is to be considered as illustrative and not limiting, the invention being limited only by the prior art and the scope of the appended claims.

Having thus described my invention, I claim:

1. A shot for the athletic field event of putting the shot, comprising a hollow die cast outer shell containing a weighting material.
2. A shot for the athletic field event of putting the shot, comprising a die cast outer shell containing a primary weighting material, and independent means for controlling the total weight of the shot.
3. A shot for the athletic field event of putting the shot, comprising a die cast outer shell containing a primary weighting material, and independent means for controlling the balance of the shot.

4. A shot for the athletic field event of putting the shot, comprising a die cast outer shell containing a primary weighting material and independent means for controlling the total weight and balance of the shot.

5. A shot for the athletic field event of putting the shot, comprising a hollow shell, a primary weighting material within said shell and a receptacle projecting inwardly from the shell adapted to receive weighting and balancing material.

6. A shot for the athletic field event of putting the shot comprising a hollow die cast shell, a primary weighting material within said shell and a receptacle projecting inwardly from the shell adapted to receive weighting and balancing material.

7. A shot for the athletic field event of putting the shot comprising a hollow shell, a primary weighting material within the shell, concave recesses in the shell to receive balancing and additional weighting material.

8. A die cast spherical shell for a shot employed in the field event of putting the shot comprising, an inner shell formed from two die cast hemispheres and an outer shell cast around the inner shell.

9. A shot for the athletic field event of putting the shot comprising a hollow die cast shell, a primary weighting material within said shell, a cylinder projecting inwardly from the surface of said shell provided with openings, weighting and balancing members within said openings, means to hold said members in position and a closure for said openings providing a continuous surface with that of the shell.

10. A shot for the athletic field event of putting the shot comprising a hollow spherical die cast shell provided with a circular opening, a cylindrical receptacle extending inwardly from the opening on the surface of said shell and provided with holes, weighting and balancing balls within the holes in said cylindrical receptacle, springs to urge said weighting and balancing balls toward the bottom of the holes, a closure for the opening in said shell to bear against the springs, a spherical surface on said closure to form a continuous surface with that of said shell, and primary weighting material within said shell.

11. A shot for the athletic field event of putting the shot comprising a hollow die cast shell with a slightly roughened surface corresponding to indentations and protrusions on the die.

12. A shot for the athletic field event of putting the shot comprising a hollow die cast shell provided with a slightly roughened surface corresponding to indentations and protrusions on the die, a primary weighting material within said shell and a receptacle projecting inwardly from the shell adapted to receive weighting and balancing material.

13. A shot for the athletic field event of putting the shot comprising a hollow spherical die cast shell provided with a plurality of circular openings, cylindrical receptacles extending inwardly from the openings on the surface of said shell and provided with holes, weighting and balancing balls within the holes in said cylindrical receptacles, springs to urge said weighting and balancing balls toward the bottom of the holes, closures for the openings in said shell to bear against the springs, a spherical surface on said closures to form a continuous surface with that of said shell, and primary weighting material within said shell.

14. A shot for the athletic field event of put-

ting the shot comprising a hollow spherical die cast shell provided with a plurality of circular openings, said spherical shell including an inner shell formed from two die cast hemispheres and an outer shell cast around said inner shell, cylindrical receptacles extending inwardly from the openings on the surface of said shell and provided with holes, weighting and balancing balls within the holes in said cylindrical receptacles, 10 springs to urge said weighting and balancing balls toward the bottom of the holes, closures for the openings in said shell to bear against the springs, a spherical surface on said closures to form a continuous surface with that of said shell, and primary weighting material within said shell.

15. A shot for the athletic field event of putting the shot comprising a hollow spherical die cast shell provided with diametrically opposed 20 circular openings, cylindrical receptacles extending inwardly from the openings on the surface of said shell and provided with holes, weighting and balancing balls within said holes in said cylindrical receptacles, springs to urge said 25 weighting and balancing balls toward the bottom of said holes, closures for the opening in said shell to bear against the springs, a spherical surface on said closure to form a continuous surface with that of said shell, and primary 30 weighting material within said shell.

16. A shot for the athletic field event of putting the shot comprising a shell, primary weighting material within the shell, a reentrant receptacle communicating with an opening in said 35 shell, for receiving additional weighting and balancing material, and a detachable closure for said receptacle.

17. A shot for the athletic field event of putting the shot comprising a two part shell, means 40 for joining the two parts of said shell, primary weighting material within the shell, a reentrant receptacle communicating with an opening in said shell, for receiving additional weighting and balancing material, and a detachable closure for 45 said receptacle.

18. The process of making a shot for the athletic field event of putting the shot comprising die casting the shell in two portions at least one of which is integrally cast with a reentrant receptacle and one with an aperture for the insertion of primary weighting material, joining the two parts of the die cast shell, introducing primary weighting material into the shell, adjusting the weight and balance of the shot by inserting additional weighting and balancing material in the reentrant receptacle and closing said receptacle.

19. The process of making a shot for the athletic field event of putting the shot comprising die casting an inner shell in two portions at least one of which is integrally cast with a reentrant receptacle and one with an aperture for the insertion of primary weighting material, joining the two parts of the die cast shell, die casting a substantially complete sphere around 20 the inner shell, introducing primary weighting material into the completed shell, adjusting the weight and balance of the shot by inserting additional weighting and balancing material into the reentrant receptacle and closing said receptacle.

20. The process of making a hollow spherical shell for a shot used in the athletic field event of putting the shot, comprising die-casting an inner shell in two portions, joining the two portions of the inner shell, and die-casting a substantially complete sphere around the inner shell.

21. The process of making a shot for the athletic field event of putting the shot, which comprises die-casting the shell in a die provided 35 with indentations and protrusions arranged in a predetermined manner to produce a slightly roughened surface on the shell corresponding to the indentations and protrusions on the die.

22. A shot for the athletic event of putting 40 the shot, comprising a hollow inner shell of two complementary portions and an outer one piece substantially completely spherical shell enveloping said inner shell.

SAMUEL ALFRED TENISON.
